UNITED STATES PATENT OFFICE.

STANLEY L. FISHER, OF CHESTER, CONNECTICUT, ASSIGNOR TO PRATT READ PLAYER ACTION COMPANY, OF DEEP RIVER, CONNECTICUT.

PNEUMATIC-CONTROL DEVICE.

Application filed October 23, 1920. Serial No. 418,878.

This invention relates to a pneumatic control device, and more particularly to a pneumatic control device to be used with the power pneumatics which are employed in 5 automatic musical instruments. The device, however, is of broad and general application, as it may be used with power pneumatics of any character. It is particularly adapted to 10 control the expression pneumatics in player pianos and similar instruments, these pneumatics in turn controlling the degree of exhaust maintained in the wind chest by the exhausting devices, the position of the hammer rest rail or the tempo valve.

15 One object of my invention is to provide a new and improved valve control for power pneumatics.

Another object of my invention is to provide a valve control system which will be 20 positive in its operation and prompt in its response to changes of pressures.

A still further object of my invention is to provide an improved valve control system in which the manual control of the 25 power pneumatics is supplemented by note sheet control.

Another object of my invention is to provide a manual control for the expansion and collapse of the power pneumatic and a note 30 sheet control which will restore the power pneumatic to its original condition, regardless of the position of the manual control.

To these and other ends the invention consists in the novel features and combinations 35 of parts to be hereinafter described and claimed.

In the accompanying drawings:

Fig. 1 is a perspective view of the valve 40 chest containing my pneumatic control device, certain associated parts being shown more or less diagrammatically.

Fig. 2 is a sectional view on line 2—2 of Fig. 1.

Figs. 3, 4 and 5 are sectional views on lines 45 3—3, 4—4, and 5—5 respectively of Fig. 2.

Figs. 6 and 7 are sectional views similar to Fig. 2, but showing the valves in other positions of operation.

As has been stated, my improved control 50 device may be used with power pneumatics of various kinds and for various purposes. However, I have chosen to illustrate one embodiment of my invention as applied to an expression pneumatic used to control a valve 55 which may be assumed to be the expression

regulating valve which controls the exhausting of the air from the wind chest of the instrument by the pumps. This expression pneumatic is shown at 55 as having an arm 56 attached to the movable leaf thereof, and 60 the arm 56 is attached by a link 57 to the expression valve 58 controlling a port 59.

To control the operation of the expression pneumatic 55, I have provided a pneumatic 65 controlling valve chest 60, which embodies 65 the improved control device of my invention. This valve chest contains three chambers 61, 62 and 63, which contain respectively the diaphragm pouch members 64, 65 and 66. In the chamber 61 is a double 70 valve 66^a of the primary type, which controls a passage 67 leading from the top of the valve chest to the chamber 61. A duct 68 communicates with the passage 67 and extends laterally to the edge of the block 75 60. This passage 68 contains a nipple 69, which is connected to a nipple 70 by the tube 71. The nipple 70 is in communication with the pneumatic 55 through the port 72 in the base or fixed leaf of the pneumatic. The 80 base of the valve 66^a rests upon the diaphragm 64 and the part of the chamber 61 which is above this diaphragm is in communication with the exhaust through the duct 73 as shown in Fig. 3. The part of 85 the chamber 61 below the diaphragm 64 is provided with a bleed opening 74, which communicates with the duct 73. The diaphragm 65, which is secured in the chamber 62, carries on its lower side a valve 75, 90 which controls a port 76, from which a duct 77 leads to the chamber 61 below the pouch 64. A stop 78 is provided to limit the movement of the valve 76. A second port 79 leads into the chamber 62 below the 95 diaphragm 65, and this port, is, through a nipple 81 and a tube 82, in communication with a valve port 83, which is controlled by a valve 83^a, manually operated by a push button 84 located in the key slip 84^a. 100

It will be apparent that as long as the valve port 83 remains closed to the atmosphere, the chambers 61 and 62 will be exhausted below the diaphragms 64 and 65 through the bleed opening 74, these diaphragms falling 105 to their lower positions and allowing the valve 75 to close the port 76 and the double valve 66^a to shut off the air from the duct 68 and will cause the pneumatic 55 to be exhausted through the duct 68, chamber 61 110

and the duct 73. The expression valve 58 will upon the collapse of the pneumatic 55 be raised from its seat and a high degree of exhaust will be maintained in the wind chest.

When the button 84 is depressed, thus allowing the air to flow into the port 83 through the tube 82 and the nipple 81, the diaphragm 65 will be raised, carrying with it the valve 75, so that the air will pass through the duct 77 to the chamber 61 below the diaphragm 64 raising this diaphragm and the double valve 66^a, so that the passage 67 will be cut off from the exhaust duct 73 and the pneumatic 55 will be flushed with air through the tube 71 and the passage 68.

To provide a supplemental note sheet control for the pneumatic 55, the third chamber 63 is provided with a passage 85 extending upward from the chamber through the top of the controlling chest 60. The ends of this passage are controlled by the double valve 86, which rests upon the diaphragm 66, and a duct 87 leads from the passage 85 to the chamber 62 above the diaphragm 65. The chamber 63 is exhausted through a duct 88, which communicates with this chamber above the diaphragm 66 and a bleed opening 89, which communicates with the duct 88 and the chamber 63 below the diaphragm 66. This portion of the chamber 63 below the diaphragm 66 is provided with a port 90, which through a nipple 91 and tube 92 is connected to a perforation 93 in the tracker bar 94. The note sheet, a fragment of which is shown at 95, will contain perforations 96 on the margin thereof, which will cooperate with the perforation 93 in the tracker bar.

The operation of my device is as follows:

When both the valve port 83 is closed by the valve 83^a and the perforation 93 in the tracker bar is closed by a solid portion of the note sheet, the valves in the valve chest 60 will be in the positions shown in Fig. 2. It will be seen that exhaust tension will be present in all of the chambers and ducts, the chambers 61 and 63 being exhausted by the ducts 73 and 88 and the bleed openings 74 and 89. While that part of the chamber 62 below the diaphragm 65 will be exhausted through the bleed opening 74 and that part of the chamber 62 above the diaphragm 65 will be exhausted through the duct 88. When the valves are in this position, the expression pneumatic will be collapsed, as shown in Fig. 1, being exhausted through the tube 71 and the ducts 68 and 73. It will be understood that the valve 66^a may, if desired, be so arranged that the expression pneumatic will be flushed with air when this normal position of the valves obtains, it being obvious that the parts may be arranged so that the expression pneumatic

may be normally collapsed or expanded as desired. The position shown will be understood, therefore, to be only for the purpose of illustration. Suppose now the operator depresses the push button 84 and moves the valve 83^a from its seat, thereby uncovering the valve port 83. This will allow the admission of air through the valve port 83 below the diaphragm 65, and as the chamber 62 is subject to exhaust tension above this diaphragm, the same will be raised and allow the air admitted through the port 83 to pass below the valve 75 into the port 76 and through the duct 77 into the chamber 61 below the diaphragm 64. The valve 66^a will then be raised, thus shutting off the duct 68 from the exhaust duct 73 and allowing air to enter at the top of the duct 67 and to flow into the pneumatic 55. The pneumatic will now be expanded and allow the valve 58 to move towards its seat. This position of the parts is shown in Fig. 6 of the drawings. If now the operator removes his finger from the valve 84, the parts will return to their normal positions shown in Fig. 2.

While the valve 84 is depressed and the parts are in the position shown in Fig. 6, suppose now that a perforation 96 in the note sheet uncovers a port 93 in the tracker bar. This will allow the admission of air through the duct 92 into the chamber 63 below the diaphragm 66. The valve 86 will now be raised, closing off the duct 87 from the exhaust duct 88 and allowing air to enter through ducts 85 and 87 into the chamber 62 above the diaphragm 65. With both ports 83 and 93 open, atmospheric air will be admitted to the chamber 62 on both sides of the diaphragm 65. The part of this chamber below the diaphragm will, however, be subjected to exhaust through the bleed 74 and for this reason the pressure below the diaphragm will be slightly reduced and the valve 75 will be drawn down upon the port 76. This will close the outlet port 76, so that any air which is admitted to the chamber 62 below the diaphragm 65 will not reach the chamber 61 below the diaphragm 64 and will, of course, have the same effect as if the valve 83 were closed. The chamber 61 below the diaphragm 64 will now be exhausted through the bleed 74, the valve 66^a will drop and the pneumatic 55 will now be exhausted and will collapse, raising the valve 58 from its port and restoring it to its normal position. The position of the parts under these conditions, when both the ports 83 and 93 are open, is shown in Fig. 7 of the drawings. This condition will, of course, only last while the perforation in the note sheet is in register with the perforation in the tracker bar and when the perforation in the note sheet has passed over the tracker bar, the valve 86 will drop down to its orig- 139

inal position, due to the air below the diaphragm 66 being exhausted through the bleed 89 and the air above the diaphragm 65 will be exhausted through the duct 88 and the diaphragm 65 will be raised, due to the atmospheric pressure below this diaphragm caused by the air flowing in through the port 83, which is still open. The parts will now be restored to the position shown in Fig. 6.

It will be apparent that I have provided means, including the valve 83 and the ducts 81, 79 and 77, for controlling primarily the position of the valve 66^a. While this valve is under the control of the push button 84, there is provided means consisting of the valve 86 controlled by the port 93 in the tracker bar for restoring the valve 66^a to its original position. If the port 93 is uncovered by a perforation in the note sheet and the valve 84 is then depressed, the valve 65 will be retained upon the port 76 closing the same, and the opening of the valve 83 will have no effect. Therefore, when the valve 86 is in its raised position, admitting air through the ducts 85 and 87 to the chamber 62 above the diaphragm 65, the valve 66^a and the pneumatic 55 will always be in the position shown in Fig. 7, regardless of the position of the valve 83^a.

It will be apparent that the port 79 serves as an inlet port to admit air to the chamber 62 below the diaphragm 65, and that the duct 77 serves as an outlet to carry this air to the chamber 61 below the diaphragm 64. The valve 75, when actuated, serves as a means to close this air course which consists of the tube 82, the nipple 81, the port 79, and the duct 77, by closing the outlet port 76. The bleed 74, by being situated between this part of the air course which may be closed to prevent the supply of air from reaching the chamber 61 and the diaphragm 64, will exhaust this part of the air course and cause the valve 75 to close at the proper time.

While I have illustrated and described a specific embodiment of my invention, it is to be understood that the same is not to be restricted to the exact details shown, but it is capable of many modifications and variations, which will fall within the spirit of the invention and within the scope of the appended claims.

I make no claim in this application to the combination of an expression valve, means to move said valve to vary the tone effects controlled thereby and separate means to restore said valve to its original position, as such claims are incorporated in my co-pending application, Serial No. 418,877, filed Oct. 23, 1920.

The term controlling valve, as used in this application, refers to the valve 66^a, which controls the power pneumatic 55.

What I claim is:

1. In a pneumatic control device, a power pneumatic, a valve to control the admission of atmosphere and exhaust to said pneumatic, means to supply air below said valve to move the same and means, independent of said first named means, to cut off said air supply. 70

2. In a pneumatic control device, a power pneumatic normally in one condition of collapse or expansion, means for changing the pneumatic from one condition to the other, and means for restoring the original condition of the pneumatic while said changing means is still in its operative position. 75

3. In a pneumatic control device, a power pneumatic, a duct communicating with said pneumatic, a valve to open said duct to atmosphere or exhaust to control the admission of atmosphere or exhaust to said pneumatic, a second pneumatic to control said valve, an air course leading to said last-named pneumatic to supply atmospheric air thereto, and means to obstruct said air course intermediate its ends to prevent the passage 85 of air therethrough. 85

4. In a pneumatic control device, a power pneumatic, a duct communicating with said pneumatic, a valve to open said duct to atmosphere or exhaust to control the admission of atmosphere or exhaust to said pneumatic, a second pneumatic to control said valve, an air course leading to said last-named pneumatic to supply atmospheric air thereto, and pneumatic means to obstruct 95 said air course intermediate its ends to prevent the passage of air therethrough. 100

5. In a pneumatic control device, a controlling valve, means operable to move said valve from one position to another, and means to restore said valve to its original position while said moving means is still in operative position. 105

6. In a pneumatic control device, a diaphragm, a valve operated thereby, means 110 operable to supply air below said diaphragm to operate the same, and means to cut off said air supply from said diaphragm while said supply means is still in operative position.

7. In a pneumatic control device, a chamber provided with an outlet port and an inlet port, a valve in said chamber operable to close said outlet port, a pneumatic in said chamber to operate said valve, and means including a second valve to control the operation of said pneumatic. 115

8. In a pneumatic control device, a chamber, a diaphragm dividing said chamber into two parts, one part of said chamber being provided with inlet and outlet ports, said diaphragm carrying a valve cooperating with one of said ports, and the other part of said chamber being provided with a port through which air or exhaust may be alternately admitted to actuate said valve. 125 130

9. In a pneumatic control device, a controlling valve, a diaphragm to operate the same, means providing a valved port through which air may be admitted to actuate the diaphragm, an air course leading from said valved port to said diaphragm, and means for closing an intermediate portion of said air course to cut off the supply of air admitted through said port.
10. In a pneumatic control device, a controlling valve, a diaphragm to operate the same, means providing a valved port through which air may be admitted to actuate the diaphragm, an air course leading from said valved port to said diaphragm, and means for closing an intermediate portion of said air course to cut off the supply of air admitted through said port, said air course being provided with a bleed opening between said diaphragm and said intermediate closable portion.
11. In a pneumatic control device, a controlling valve, a diaphragm to operate the same, means providing a valved port through which air may be admitted to actuate the diaphragm, an air course leading from said valved port to said diaphragm, means providing a second port, and means controlled by the opening and closing of said second port for closing an intermediate portion of said air course to prevent operation of said valve by air entering through said valved port.
12. In a pneumatic control device, a controlling valve, means to operate said valve including a valve port through which air may be admitted and means including a second air port to restore said valve to its original position while said first port is still open.
13. In a pneumatic control device, a controlling valve, a valved port adapted to be opened to operate said valve, and note sheet controlled means to restore said valve to its original position while said valved port is still open.
14. In a pneumatic controlling device, a controlling valve normally occupying a given position, means including a valved port to move said valve from its normal position, and means to restore said valve to its normal position and retain it therein whether said valved port is open or closed.
15. In a pneumatic controlling device, a power pneumatic, a controlling valve movable to control the same, means including an air port to move said valve, and note sheet controlled means to restore said valve to its original position whether said air port is open or closed.
16. In a pneumatic control device, a controlling valve, means to move said valve from its normal position, and means to temporarily restore said valve, movable in a single direction to its original position and return it to the position to which it was moved.
17. In a pneumatic control device, a controlling valve, means to admit air below said valve to operate the same, and note sheet controlled means to temporarily restore said valve to inoperative position during the admission of air through said means.
18. A power pneumatic, a control device therefor comprising a chest, said chest containing a valve chamber, a valve therein to control said power pneumatic, a second chamber in said chest, a duct leading from said second chamber to said first chamber, and means in said second chamber to close said duct.
19. A power pneumatic, a control device therefor comprising a chest, said chest containing a valve chamber, a valve therein to control said power pneumatic, a second chamber in said chest, a duct leading from said second chamber to said first chamber, a duct to admit air to said second chamber, said ducts communicating with each other through said chamber and means for cutting off said communication.
20. A power pneumatic, a control device therefor comprising a chest, said chest containing a valve chamber, a valve therein to control said power pneumatic, a second chamber in said chest, a duct leading from said second chamber to said first chamber, a duct leading into said second chamber and communicating with said first duct therethrough and a valve in said second chamber for cutting off said communication.
21. A power pneumatic, a control device therefor comprising a chest, said chest containing a valve chamber, a valve therein to control said pneumatic, an air course leading into said valve chamber, said chest having a second chamber forming a part of said air course and means in the second chamber for closing said air course.
22. In a pneumatic control device, a power pneumatic, a valve controlling the admission of atmosphere or exhaust to said pneumatic, a second pneumatic to control, said valve, an air course leading to said last named pneumatic to supply atmospheric air thereto, said air course including a chamber and air ducts leading into and out of said chamber, a diaphragm spanning said chamber and provided with a valve closing one of said ducts, the communication of said ducts with said chamber being upon one side of said diaphragm, and means to supply atmospheric air to said chamber upon the other side of said diaphragm.
23. In a pneumatic control device, a power pneumatic, a valve controlling the admission of atmosphere or exhaust to said pneumatic, a second pneumatic to control said valve, a manually controlled air course leading to said last named pneumatic to supply atmos-

pheric air thereto, said air course including a chamber, and air ducts leading into and out of said chamber, a diaphragm spanning said chamber and provided with a valve closing one of said ducts, the communication of said ducts with said chamber being upon one side of said diaphragm, and note sheet controlled means to supply atmospheric air to said chamber upon the other side of said diaphragm.

24. In a pneumatic control device, a controlling valve means to move said valve from its normal position and continuously moving means to temporarily restore said valve to its original position.

25. In a pneumatic control device, a controlling valve means to move said valve from its normal position, and means movable to temporarily restore said valve to its original position, and upon a continued movement thereof in the same direction to permit the valve to again move from its normal position.

26. In a pneumatic control device, a port, a pneumatic carrying a valve to control said port, means for admitting atmospheric air

to both sides of said pneumatic, and a bleed to reduce the pressure on one side thereof to operate the same.

27. In a pneumatic control device, a chest presenting a chamber, a diaphragm in said chamber, means for admitting air upon either side of said diaphragm, a duct leading from said chamber and controlled by the diaphragm, said duct being in restricted communication with a source of exhaust to reduce the pressure upon one side of the diaphragm to operate the same.

28. In a pneumatic control device, a chest having a pair of valve chambers provided with operating pneumatics and valves, a third chamber in said chest and a pneumatic in said chamber, a duct leading from one of said valve chambers to one side of said pneumatic, a duct leading from the other side of said pneumatic to the other valve chamber below the diaphragm therein, and means to admit air to the last named side of said pneumatic in said third chamber.

In witness whereof, I have hereunto set my hand on the 20th day of October, 1920.

STANLEY L. FISHER.

CERTIFICATE OF CORRECTION.

Patent No. 1,626,192.

Granted April 26, 1927, to

STANLEY L. FISHER.

It is hereby certified that error appears in the printed specification of the above numbered patent requiring correction as follows: Page 4, line 36, claim 12, for the word "valve" read "valved"; same page, lines 64 and 65, claim 16, ~~strike out the comma and words~~, "movable in a single direction" ~~and~~ insert the same to follow after the word "means" in line 63; and that the said Letters Patent should be read with these corrections therein that the same may conform to the record of the case in the Patent Office.

Signed and sealed this 31st day of May, A. D. 1927.

Seal.

M. J. Moore,
Acting Commissioner of Patents.
